UNITED STATES PATENT OFFICE.

HENRY H. HIGERT, OF INDIANAPOLIS, INDIANA.

DESIGN FOR A HEATING-STOVE.

No. 38,497.

Specification for Design.

Patented March 26, 1907.

Application filed February 12, 1906. Serial No. 300,810. Term of patent 7 years.

To all whom it may concern:

Be it known that I, HENRY H. HIGERT, a citizen of the United States, residing at Indianapolis, in the county of Marion and State of Indiana, have invented a new, original, and ornamental Design for Heating-Stoves, of which the following is a specification.

The figure in the drawing illustrates my new design.

I claim—

The ornamental design for a heating-stove, as shown.

HENRY H. HIGERT. [L. s.]
